ALBERT E. VANDERCOOK, OF ALAMEDA, CALIFORNIA, ASSIGNOR, BY MESNE ASSIGNMENTS, TO CALIFORNIA MACVAN CO., OF SAN FRANCISCO, CALIFORNIA, A CORPORATION OF CALIFORNIA.

AGITATOR.

1,156,946.

Specification of Letters Patent.

Patented Oct. 19, 1915.

original application filed November 13, 1913, Serial No. 800,721. Divided and this application filed March 26, 1914. Serial No. 827,472.

To all whom it may concern:

Be it known that I, ALBERT E. VANDERCOOK, a citizen of the United States, and a resident of Alameda, county of Alameda, 5 and State of California, have invented certain new and useful Improvements in Agitators, of which the following is a specification.

This application is a division of my prior 10 application Serial Number 800,721, filed in the United States Patent Office on November 13, 1913.

The invention relates to an apparatus for producing the agitation of liquid, fluid 15 slimes or pulp, by means of movable jets of liquid, fluid slimes or pulp discharging within the mass to be agitated.

One object of the invention is to provide a practical and efficient agitator of this type. 20 Another object of the invention is to provide an agitator of this type which is operable in connection with thick slimes and pulps.

Another object of the invention is to provide 25 an agitator of this type in which the rotating element and its support are arranged out of contact with the bottom of the containing vessel.

A further object of the invention is to 30 provide an agitator of this type in which a higher discharge pressure of the jets is obtainable than has heretofore been practical.

The invention possesses other advantageous features, which, with the foregoing, 35 will be set forth at length in the following description where I shall outline in full that form of the invention which I have selected for illustration in the drawings accompanying and forming part of the present specification. The novelty of the invention will be included in the claims succeeding said description. From this it will be apparent that I do not limit myself to the showing made by said drawings and description, as 45 I may adopt many variations within the scope of my invention as set forth in said claims.

Referring to said drawings: Figure 1 is a vertical section of a tank showing the agitator of my invention arranged therein. Fig. 2 is an elevation, partly in section, of the bearing arranged between the stationary and rotatable parts of the agitator.

The agitator of my invention is particularly adapted for use in metallurgical operations for agitating or mixing pulps or slimes or for mixing solutions with pulps or slimes. The agitator is rotated by the reaction of jets of liquid, slimes or pulp, which are discharged therefrom, and such liquid, slimes or pulp, may be withdrawn from the mass or body being agitated or mixed or may be drawn from an independent source.

A great many manufacturing, metallurgical, chemical and other processes are now carried or assisted by the use of an electric current, and in such processes where the electric current is applied or passed through a liquid or semi-solid, a rotating element is 65 employed for various purposes and this element usually forms one electrode or terminal of the electric circuit and a plate arranged in the bottom of the containing vessel 70 usually forms the other electrode or terminal of circuit, the two electrodes being separated from each other so that the current will pass through the liquid. As far as I am aware, in apparatus for carrying out such processes, the stationary portion of the 75 bearing is invariably arranged in or on the bottom of the vessel and insulation is generally relied upon to insulate this stationary portion, which, of course, is in direct contact with the rotating portion, from the 80 plate or electrode arranged in the bottom of the vessel. This method of insulating the two electrodes has been very unsatisfactory 85 and has presented many difficulties. In accordance with my invention, I space the entire bearing from the bottom plate or electrode, so that there is no liability of short circuiting the current, which must pass through the liquid. It is to be understood, however, that the agitator of my invention 90 is not limited to use in connection with an electric current and that the foregoing statement in regard to its use in connection with an electric current simply states one of its advantages.

Submerged rotating structures which are rotated by the reaction of jets of liquid and which are provided with liquid sealed bearings are usually of the underfeed type, that is, the liquid which is introduced into the 105 rotating structure is introduced from below,

through the bottom of the vessel, and this upwardly flowing stream of liquid exerts an upward pressure on the rotatable part of the bearing which tends to and often does 5 raise and unseat the rotatable structure to a sufficient degree at least to allow the liquid to gain access to the bearings. These liquids usually carry solid and semi-solid material which rapidly destroys the bearings when 10 it comes in contact therewith. By introducing the liquid from above, the pressure of this liquid assists in holding the rotating part to its seat, thereby allowing high pressures to be employed which result in a 15 greater speed of rotation of the rotating element and a greater discharge velocity of the jets.

A further advantageous feature of the agitator of my invention is that the rotatable element and bearing may be removed 20 as a whole from the vessel without allowing or causing the separation or falling apart of the various parts of the bearing, a feature which is of substantial importance.

25 In accordance with my invention, I suspend a pipe or conductor 2 centrally in the vessel 3 by means of a spider 4 or other suitable structure. This pipe 2 is held firmly against revolution and terminates 30 above the bottom of the vessel. Secured to the lower end of the depending pipe 2 is a cylindrical element 5 which is provided on its lower end with an outwardly extending flange 6. Secured to the flange 6 or formed 35 integral therewith, and spaced from the element 5, and preferably arranged parallel therewith, is an upwardly extending wall or ring 7, at the upper end of which is arranged the lower bearing race 8. This race may 40 seat on the wall 7 so that it may be removed for the purposes of repair or replacement, or may be formed integral with the wall 7. The anti-friction element of the bearing may consist of a plurality of balls 9, or rollers or 45 any other suitable construction or arrangement.

The upper bearing race 12 may be formed 50 separately and attached to the gland 13 or may be formed integral therewith. The gland 13 which forms the rotatable part of the bearing consists of a cylindrical structure, having substantially vertical walls 14-15 which are spaced apart from each other, forming therebetween a closed top 55 pocket in which is disposed at the upper portion, the balls 9 and ball races 8 and 12. The depending wall 15 extends downward adjacent and spaced from the wall 5 and terminates adjacent the flange 6. When the 60 bearing is submerged, air is entrapped in the pocket formed between the walls 14 and 15, thereby preventing the liquid from coming in contact with the balls or races. Formed at the lower end of the gland are 65 tapped bosses 16 into which the pipes or

conductors 17 of the rotating structure are screwed. These pipes 17 are provided with one or more nozzles or outlets 18 which are arranged at an angle to the pipes, so that the reaction of the liquid discharging therefrom 70 causes the structure to rotate, and these nozzles are preferably flattened at their discharge end to cause the liquid, slime or pulp, to discharge in flat streams. The nozzles 18 are preferably downwardly inclined so 75 that the discharging streams sweep the bottom of the vessel or are directed toward the bottom of the vessel. The bottom of the gland is closed by the plate 19 which is preferably formed with an elevated conical 80 center 21, which directs the liquid smoothly to the pipes or hollow arms 17. The plate 19 is spaced apart from the bottom of the tank or the electrode thereon, so that when an electric current is employed, the current 85 must pass through the liquid. When it is desirable to agitate the entire liquid in order to prevent precipitation, I usually form passages 22 in the plate 19 through 90 which liquid is discharged for the purpose 90 of agitating the liquid directly under the plate.

In order that the gland 13 may rotate freely with regard to the stationary part of the bearing, clearance must be provided between the outer edge of flange 6 and the wall 14, and while this clearance is made as small as practical the area of the annular opening thus formed is material and under the pressure of the liquid introduced through pipe 2, a large quantity of the liquid passes through 100 this opening. In order to dispose of this leakage liquid without allowing it to come in contact with the bearings, I provide one or more apertures 23 through the wall 7 105 preferably at the bottom, through which the leakage liquid passes. This leakage liquid then passes upward through the annular passage 24 between the walls 5 and 15. Covering the upper or discharge end of this 110 passage is a cap 25, which slopes downwardly, conforming to the slope of the upper surface of the gland 13. This cap is secured to the wall 5 in any suitable manner and is spaced apart slightly from the 115 upper surface of the gland, to permit the escape of the leakage liquid. This cap not only acts to divert the leakage liquid downward, (a feature which is essential in some processes) but it retards the flow of the leakage liquid, and thereby greatly reduces the amount of the leakage. The comparatively long, narrow passage between the cap and the gland produces a frictional resistance to the passage of the liquid, without materially increasing the friction between the stationary and revolving parts of the bearing. In some instances, where the liquid in the tank is very thick, therefore requiring a great 120 pressure to rotate the rotating element, I 125

have found that with the cap omitted, the amount of leakage is so great that the rotating element would not turn, but by placing the cap and reducing the leakage, that the rotatable element would turn. Since the liquid in the vessel is often opaque, it is not possible to observe the rotating element to determine its speed, or whether it is rotating at all. In order that these conditions may be noted, I form a boss 26 on the gland 13 to which I attach the vertically extending indicating rod 27, which projects above the level of the liquid and indicates the motion of the rotating element.

In operation, liquid is flowed down through the pipe 2 and out through the arms 17, causing the structure to rotate, and the leakage liquid passes through holes 23 and up through passage 24 and is discharged through the passage between the cap 25 and gland 13. The liquid rises in the pocket between the walls 14 and 15 until the pressure of the entrapped air is equal to the pressure of the liquid and the pocket is made of such height that the level of the liquid therein does not reach the bearings. In order to prevent any sloshing or surging of the liquid from throwing or splashing on the bearings, I have found it advisable to form circumferential ribs 28 and 29 on the wall 7 which extend into close relation with the walls 14 and 15, thereby forming narrow passages between the walls 14 and 15 and the wall 7, through which the liquid cannot splash. The liquid which flows downwardly in the conductor 2 may flow thereto by gravity or may be driven thereto by a pump. In the construction shown in the drawings, the liquid slimes or pulp are withdrawn from the tank 3 adjacent its upper portion through the pipe 31 which is connected to the suction side of the pump 32, whence it is forced through the pipe 33 into the depending conductor 2. The liquid, slimes or pulp pass from the conductor 2 into the hollow-armed structure which is rotatably mounted on the lower end thereof when they discharge from the nozzles 18.

While I have specifically described herein the bearing upon which I prefer to mount the rotating portion of the agitator of my invention, it is to be understood that the present invention is not limited to the specific bearing which is claimed in my prior application, Serial Number 800,721, of which this application is a division.

By the use of the agitator of my invention a thorough agitation or mixing of the liquid, slimes or pulp, may be obtained practically regardless of the thickness thereof, either by recirculating the liquid, pulp or slimes, or by introducing liquid, pulp or slimes, from an independent source. On account of the construction of the agitator, the rotating arms may be driven at a compara-

tively high velocity and the reaction produced by the discharging streams or jets is sufficient to produce rotation of the rotating element in very thick slimes or pulps.

I claim:

1. In an apparatus of the character described, a vessel, a stationary conductor depending into said vessel, and a hollow armed structure rotatably mounted on said conductor.

2. In an apparatus of the character described, a vessel, a stationary conductor depending into said vessel, and a hollow armed structure adapted to be rotated by the reaction of liquid discharging therefrom rotatably supported on the lower end of said conductor.

3. In an apparatus of the character described, a vessel, a stationary conductor depending into said vessel through which liquid passes downwardly, a hollow armed structure adapted to be rotated by the discharge of liquid therefrom arranged at the lower end of said conductor and arranged to receive liquid therefrom, and an anti-friction bearing arranged between said conductor and rotatable structure.

4. The combination with a vessel adapted to contain a liquid, of a stationary element depending into said vessel and extending below the normal surface of the liquid therein, a rotatable element mounted on said stationary element below the surface of the liquid and spaced from the bottom of said vessel, and a liquid sealed bearing arranged between said elements.

5. The combination with a vessel adapted to contain a liquid, of a stationary depending conductor through which liquid passes downwardly, extending below the surface of said liquid, a rotatable structure adapted to be rotated by the reaction of the liquid passing therethrough from said conductor, mounted on said conductor below the surface of the liquid in the vessel and spaced from the bottom of said vessel, and a liquid sealed bearing arranged between said structure and conductor.

6. The combination with a vessel adapted to contain a liquid, of a hollow rotatable structure adapted to be rotated by the reaction of the liquid passing therethrough, arranged in said vessel below the normal surface of the liquid therein and above and spaced from the bottom of said vessel, a conductor on which said structure is mounted and through which liquid is conducted to said structure, depending into said vessel, and a liquid sealed bearing arranged between said structure and conductor.

7. In an apparatus of the character described, a vessel adapted to contain liquid, a conductor depending into said vessel and extending below the normal level of the liquid therein, and a hollow armed structure

rotatably mounted on said conductor and disposed below the normal level of the liquid.

8. In an apparatus of the character described, a vessel, a stationary conductor depending into said vessel, a rotatable structure mounted on the lower end of said conductor adapted to be rotated by the reaction of liquid discharging therefrom, and 10 an upwardly extending indicator rod attached to said structure.

9. In an apparatus of the character described, a vessel, a stationary conductor depending into said vessel, a hollow armed 15 structure rotatably mounted on the lower end of said conductor and in communication therewith, a plurality of downwardly inclined nozzles on said structure, and an anti-friction bearing between said conductor 20 and structure.

10. In an apparatus of the character described, a vessel, a stationary conductor depending into said vessel, and a rotatable element mounted thereon at the lower end, 25 the lower face of said rotatable element being spaced from and being free from mechanical connection with the bottom of the vessel.

11. In an apparatus of the character described, a vessel, a stationary conductor through which liquid passes downwardly 30

depending into said vessel, a structure adapted to be rotated by the discharge of liquid therefrom arranged to receive such liquid from said conductor and a liquid 35 tight anti-friction bearing arranged between said conductor and structure.

12. In an apparatus of the character described, a vessel, a stationary conductor depending into said vessel, a hollow armed 40 structure adapted to be rotated by the discharge of liquid therefrom mounted on the lower end of said conductor, an anti-friction bearing arranged between said conductor and structure, and means for reducing 45 the liquid leakage at the juncture of said structure and conductor.

13. In an apparatus of the character described, a vessel, a stationary conductor depending into said vessel through which 50 liquid passes downwardly, a hollow armed structure adapted to be rotated by the discharge of liquid therefrom mounted on said conductor at the lower end thereof, and an anti-friction bearing for said structure. 55

In testimony whereof, I have hereunto set my hand at San Francisco, California, this 21st day of March, 1914.

ALBERT E. VANDERCOOK.
